UNITED STATES PATENT OFFICE.

ENOCH COVERT, OF FARMER VILLAGE, NEW YORK.

COMBINED GAG-RUNNER AND ROSETTE-FASTENING.

SPECIFICATION forming part of Letters Patent No. 350,043, dated September 28, 1886.

Application filed June 2, 1886. Serial No. 203,948. (No model.)

To all whom it may concern:

Be it known that I, ENOCH COVERT, a citizen of the United States, residing at Farmer Village, in the county of Seneca and State of New

- 5 York, have invented certain new and useful Improvements in a Combined Gag-Runner and Rosette-Fastening, of which the following is a specification, reference being had therein to the accompanying drawings.
- 10 My invention relates to rosette-holders and gag-runners for bridles, and the object I have in view is to combine the two in such a manner upon a single plate as to make a cheap, durable, and efficient device for both purposes.
- 15 In the accompanying drawings, making part of this specification, Figure 1 represents a side view, and Fig. 2 a plan view, of my invention.

In the figures, A represents a plate, upon 20 one side of which is a gag-runner loop, B, and upon the other a loop, C, for the purpose of securing a rosette to the bridle. The plate A may be secured to the crown-piece of the bridle either by a rivet or screw, or by a hook at 25 its upper end. The loop C passes through an opening in a rosette, and is there connected by the brow-band to the crown-piece D in the usual manner.

d represents a rosette secured in place.

The check-rein passes direct from the rings 30 in either a check or common bridle-bit to the gag-runner loop or thence back to check-hook on the saddle of the harness.

By the use of this device the benefits of an overdraw check are accomplished and with as 35 much ease and comfort to the horse as in the ordinary way of checking, and the foretop and mane are not disarranged. The loop B may be disconnected from the plate A, as shown at the upper part, so that the check-rein may be 40 placed therein from above, if so desired.

Having fully described my invention, what I claim as new, and desire to secure by Letters Patent, is—

A combined gag-runner and rosette-fastening consisting of a plate, A, having a gag-loop runner at one side, and a loop, C, on the opposite side adapted to pass through an opening in the rosette and crown-piece, and be connected by the brow-band, so as to secure the 45 50 whole together, substantially as specified.

In testimony whereof I affix my signature in presence of two witnesses.

ENOCH COVERT.
